Sam E. A. Koenigberg

UNITED STATES PATENT OFFICE

IRA STIGLITZ, OF BROOKLYN, NEW YORK, ASSIGNOR TO SUPERB BRONZE & IRON CO., INC., A CORPORATION OF NEW YORK

WINDOW

Application filed December 6, 1930. Serial No. 500,477.

The object of this invention is to provide certain improvements in the construction of double hung metal windows including as a particular object novel automatic means affording tight closure at the top and at the bottom of the window at the same time eliminating binding or jamming. Another particular object of the invention is to provide a construction of some of the frame members whereby a so-called three point contact may be obtained between certain adjacent movable parts of the window frame in order to provide tight closure and prevent binding and rattling. Other objects will appear as this specification proceeds while reference is had to the accompanying drawings in which

Figure 1 is a vertical sectional view of a double hung window construction embodying the invention with parts omitted and parts broken away.

Figure 2 is a horizontal sectional view with parts omitted and parts broken away taken on the irregular line 2-2 in Figure 1.

Referring to the drawings the window frame comprises a bottom jamb or sill 3, two side jambs 4 and 5 and a top section or top jamb 6. The sill is formed with an outer stoping portion 7, so that water may run off freely. The inner end of the sill terminates in a vertical wall 8 which is continued on the inside of the window to form an inside sill or flange 9. The sill 3 extends along the lower part of the window between the side jambs 4 and 5. These latter are alike so that the description of one of them will suffice.

Each side jamb comprises an outer covering rectangularly bent flange section 10, an intermediate relatively wide body section 12 and an inner ornamental flange section 13. The side jambs are preferably bent or shaped as shown in Figure 2, though other forms may be used. It is however a feature of the invention that the side jambs are provided with a recessed portion 14 and a groove 15. The recessed portion 14 serves to position and receive the sashes separating element or strip 16 having an inwardly projecting T-rail 17 and feet 18-18 providing a space 19 for purposes of access to the usual chains, weights

and operating parts of the window which are concealed within the jambs and not shown as they form no part of this invention. The purpose of the groove 15 will be explained later.

The top section 6, Figure 1, has an inner ornamental flange section 20 corresponding to the side jamb sections 13, an intermediate body section 21 and an outer covering flange section 22 matching the side jamb sections 10 and providing a vertical wall 23. The body section 21 has a shallow recessed portion 24 adapted to receive a top separating channel 25 the outer side of which serves as a closure portion to be presently explained.

The upper window sash comprises a top frame 27, a bottom frame 28 and two side frames 29, 29 shown dotted in Figure 2. The upper glass 30 is held within the sash frame by angle strips 31. The top frame 27 is formed with vertical flanges 32 and 33. The latter is the inner flange and is adapted to engage the separating channel 25 when the window is closed. The outer flange 32 is formed with a longitudinal horizontal pivot edge 34 upon which is pivoted a movable upper contact member 35 having a groove 36 for receiving the pivot 34, and two wings 37 and 38 adapted to engage the upper jamb sections 21 and 23.

The upper sash bottom frame 28 is formed with an inner substantially Z-shaped flange having three contact portions 39, 40 and 41.

The upper sash side frames 29 have each a vertical flange 43 adapted to engage behind the T-rail 17 on the one side thereof, and an outer flange 44 adapted to engage the outer foot 18 of separating member 16.

The lower window sash comprises a top frame 46, a bottom frame 47 and two side frames 48. The lower glass 49 is held within the lower sash frame by angle strips 50. The top frame 46 is formed with two superposed lateral outwardly projecting contact rails 51 and 52 and an outer vertical portion 53 which forms part of the glass holding members. Inwardly the top frame has a wall portion 54 forming a recess for receiving the inverted top finishing U-piece 55.

The lower sash bottom frame 47 is formed

- with vertical flanges 56 and 57. The latter is the outer flange and forms a finishing lower part of the sash. The inner flange 56 is formed with a horizontal longitudinal pivot 5 edge 58 upon which is pivoted a movable lower contact member 59 having a groove 60 for receiving the pivot 58, and two wings 61 and 62 adapted to engage the sill members 7 and 8. 63 is a finishing inner horizontal 10 flange on the frame 47. The outer flange 57 is dimensioned so as not to touch the sill 3 thereby leaving a space 64 for draining purposes. The sashes are locked in the usual manner by two cooperating lock members 65 and 66.
- 15 The lower sash side frames 67, Fig. 2, have each a vertical flange 68 adapted to engage behind the T-rail 17 on the inside thereof, and an inner flange 69 adapted to engage in the groove 15 in the side jambs 5.
- 20 Referring now to Figure 1 it will be seen that when the window is closed, the two sashes engage with a three point contact construction because of the engagement of the upper sash elements 39, 40 and 41 with the 25 lower sash elements 51, 52 and 53, the parts being forced together by the lock 65—66.

At the top of the window there is also a three point closing contact because of the engagement of the wings 37 and 38 of the movable member 35 with the upper jamb members 23 and 21, together with the third engagement point between the members 33 and 25. At the bottom there is a two point engagement contact between the wings 61 and 35 62 of the movable member 59 with the sill members 7 and 8.

When the lock 65—66 is unlocked, the upper sash lower frame and the lower sash upper frame naturally spring apart or are loosened 40 so as to move easily. If now the lower sash is raised, it will be seen that there is no binding to overcome. The raising movement naturally and automatically causes the movable member 59 to tilt counter clockwise thereby 45 automatically disengaging the wing 62 from any binding contact with the flange 8. Similarly, when the upper sash is lowered, the tilting action of the pivoted member 35 results in an automatic disengagement of said 50 member with the top jamb members 21 and 23, and in addition permits easy sliding disengagement between the flanges 33 and 25.

On the other hand, when the upper sash is moved up into closing position, the upward 55 thrust of the pivot edge 34 will cause a counter clockwise movement of the two wing members 37 and 38 with the result that it will engage the upper jamb tightly and also force the vertical flange 33 tightly against the separating channel 25.

The movable locking members 35 and 59 60 hang free on their respective pivot edges 34 and 58 upon which they are mounted by a sliding endwise movement. When the sashes are moved into closed positions, these

members adjust themselves automatically into tight locking non-binding engagement with the corresponding cooperating parts of the jamb members.

Coming now to the sash side frames it will be seen from Figure 2, that the side frames 29 and 67 of the upper and lower sashes respectively, provide three points contact in cooperation with the side jambs as follows. The upper sash member 44 engages the jamb 75 member 18, and the member 43 engage the T-rail 17 at two points as shown. Similarly for the lower sash members of which 69 engages the jamb in the groove 15 while the member 68 makes a two point contact with the T-rail 17.

It will therefore be seen that this invention provides a metal double hung window construction with three points of non-binding contact on all sides except at the bottom of the window. The movable contact members 35 and 59 afford particularly non-binding tight closure in an automatic manner by self adjustment.

While the invention has been disclosed as applicable to a metal window nevertheless it will be understood that the principle of the invention is applicable to other forms of windows or doors, transoms and the like.

I claim:

1. In a window structure of the character described, a window jamb, a window sash in movable relation thereto and means on said sash in pivotal relation to the sash providing tight contact between the said jamb and one edge of the sash when the latter is closed.
2. In a window structure of the character described, a window jamb, a window sash in movable relation thereto and pivoted means on said sash automatically operable when the sash is closed for providing tight contact between the window jamb and one edge of the sash.
3. In a window structure of the character described, a window jamb, a window sash in movable relation thereto and pivoted means on one edge of the said sash automatically operable when the sash is closed for providing tight contact between the window jamb and one edge of the sash.
4. In a window structure of the character described, a window jamb, a window sash in movable relation thereto, means providing tight closure between the sash and the jamb comprising a member pivoted on one edge of the sash and adapted to engage a fixed member on the said jamb when the sash is closed.
5. In a window structure of the character described, a window jamb, a window sash in movable relation thereto and a member pivoted on one edge of the sash and extending along the same the length thereof providing tight closure between the said jamb and one edge of the sash when the latter is closed.
6. In a window structure of the character

- described, a window jamb, a window sash in movable relation thereto, means on said jamb providing angularly disposed contacting walls and a member pivoted on said window sash on one edge thereof adapted to automatically engage said contacting walls to provide tight closure between the window sash and the jamb.
7. In a window structure of the character described, a window jamb, a window sash in movable relation thereto, means providing tight closure at a plurality of contacting points between the said jamb and sash comprising angularly disposed walls formed in said jamb, a contacting member pivoted on and along one edge of the sash and adapted to automatically engage the said walls.
8. In a window structure of the character described, a window jamb, a window sash in movable relation thereto, angularly disposed walls formed in said jamb, and a fixed member and a movable member on said sash arranged in parallelism along one edge thereof for engagement with said angular walls to afford tight closure between said sash and jamb.
9. A window structure of the character described, a window jamb, a window sash in slidable relation thereto, angularly disposed walls formed in the top section of said jamb, a fixed member and a movable member extending along the top of said sash and adapted to enter between and engage said angularly disposed jamb walls to afford tight closure at a plurality of points of engagement between the top of the jamb and the top of the window sash.
10. Closing means for the top section of a window jamb and the top of a window sash comprising in combination angularly disposed spaced walls formed in the window jamb, a fixed member on the window sash adapted to engage one of said jamb walls and a movable member on said window sash adapted to automatically engage others of said jamb walls when the sash is closed and to exert a closing pressure on said fixed member.
11. Closing means for the top section of a window jamb and the top of a window sash comprising in combination angularly disposed spaced walls formed in the window jamb, a fixed member on the window sash adapted to engage one of said jamb walls and a movable member on said window sash adapted to automatically engage others of said jamb walls when the sash is closed and to exert a closing pressure on said fixed member, said fixed and movable sash members being arranged in parallelism along the top of the window sash.
12. Closing means for a window jamb and a window sash comprising in combination angularly disposed flanges formed in the jamb and a member pivoted on and extend-
- ing along one edge of the window sash for automatic closing engagement with said jamb flanges.
13. Closing means for window sashes comprising in combination a pivot edge member on the sash, a closing member formed with a jamb portion for pivotal engagement with said pivot edge member and contacting portions to both sides of the said jamb portion, said closing member extending the length of the sash at one side thereof.
14. Closing means for window sashes comprising a member adapted to be mounted on a window sash along one edge thereof and consisting of a centrally disposed grooved body portion and contacting wing portions extending therefrom to both sides for the purpose set forth.
15. In a window structure in combination with the window jamb an upper and a lower window sash and fixed means on said sashes providing tight closure at a plurality of points between said sashes and between the latter and the window jamb, and movable means on said sashes providing tight closure at other points between the sashes and the window jamb, said movable means being automatically operable upon the closing of the window sashes.
- Signed at Brooklyn, in the county of Kings and State of New York this 4th day of December, A. D. 1930.
